UNITED STATES PATENT OFFICE.

JAMES F. HEYWARD, OF WILMINGTON, DELAWARE, ASSIGNOR TO THE DELAWARE AIR SPRING MANUFG. COMPY.

PNEUMATIC SPRING.

Specification of Letters Patent No. 13,248, dated July 10, 1855.

To all whom it may concern:

Be it known that I, JAMES F. HEYWARD, of Wilmington, in the county of Newcastle and State of Delaware, have invented a certain new and useful Improvement in Pneumatic Springs; and I do hereby declare the following to be a full, clear, and exact description thereof, reference being had to the accompanying drawings, making a part of this specification, in which—

10 Figure 1, represents a view of the under side of the spring and Fig. 2, represents a transverse sectional view of the same.

15 The nature of my invention consists, in employing a fluid piston, playing in an air chamber of any form, in such a manner, that when the fluid piston is forced against the contained air, it will compress the same to such an extent as to cause the resistance 20 of its elasticity to balance the force applied. This fluid piston being moved through the intervention of any flexible inextensible water-proof bottom, securely fastened to the lower margin of the air chamber.

25 To enable others skilled in the art to make and use my invention, I will proceed to describe its construction and operation.

A is a metallic cylinder open at the bottom, with a flange B, B, projecting from its 30 lower margin. L is a thick sheet of india rubber, extending from outside to outside of the flange B, B, and closing the opening of the cylinder so as to render it water tight. The gum has a considerable deviation down- 35 ward from the plane of the mouth of the cylinder as shown in the drawing.

G is a sheet of leather or any other flexible inextensible material of the same dimensions and outline as the sheet of india rubber L, just described. Its use is merely to afford support to the gum.

P is a rod passing through the center of

the gum and leather bottom, with a shoulder inside and a nut outside, by means of which the gum and leather may be so compressed 45 as to leave the vessel still perfectly watertight. The object of the rod P is to insure the movement upward in a straight line of the flexible bottom, which is effected by causing it to play in the hollow cylinder C, 50 which forms part of the top of the air chamber A.

R is an iron ring, drawn up by the bolts b, b, pressing the india rubber and leather against the flange of the cylinder so as to 55 render the whole watertight.

The space between the red line and gum, shows the position of the fluid piston, which moves upward, compressing the air in the top of the air chamber, whenever the flexible bottom is exposed to pressure.

H, is a tube passing through the flange of the cylinder, communicating with the inside of the cylinder, through which the air is forced into it, by means of any air pump. 65 The opening may be closed by any known arrangement of stop-cock, care however must be had, that its inner opening must always be below the level of the water surface constituting the piston.

Having thus fully described the nature of my improvement in pneumatic springs, what I claim therein as new and desire to secure by Letters Patent, is—

The method of rendering available the 75 elasticity of aeriform bodies in the construction of springs, bumpers &c., by employing a fluid piston to effect their compression substantially as described.

J. F. HEYWARD.
